UNITED STATES PATENT OFFICE.

ELЛИCK H. GOLLINGS, OF CHICAGO, ILLINOIS, ASSIGNOR TO THE GOLLINGS BI-CENTRIC PUMP COMPANY, OF SAME PLACE.

ROTARY PUMP.

SPECIFICATION forming part of Letters Patent No. 448,518, dated March 17, 1891.

Application filed May 31, 1890. Serial No. 353,689. (No model.)

To all whom it may concern:

Be it known that I, ELЛИCK H. GOLLINGS, of Chicago, in the county of Cook and State of Illinois, have invented certain new and useful 5 Improvements in Rotary Pumps; and I do hereby declare that the following is a full, clear, and exact description thereof, reference being had to the accompanying drawings, and to the letters of reference made thereon, 10 which form a part of this specification.

This invention has for an object to provide an improved construction in rotary pumps.

In certain prior applications for patents filed by me—towit, Serial Nos. 301,675, 315,250, 15 333,766, and 333,767—I have described rotary pumps in each of which is employed a non-rotating shaft having an eccentric portion, a rotating shell mounted on the concentric portion of said shaft, and a chambered or winged 20 wheel within the shell and mounted on the eccentric portion of the shaft, the shell and wheel rotating together by force applied to the shell and operating upon the wheel through suitable engagement of the shell with the wheel, 25 and the fluid to be pumped entering and emerging through the non-rotating shaft, which is made hollow for that purpose.

In the present construction the shell is made stationary or non-rotative and the shaft 30 rotates. The chambered or winged wheel is mounted on the eccentric portion of said shaft and by engagement with the shell is held from rotation, so that it only gyrates within the latter as the shaft turns.

35 In all of those constructions set forth in said prior applications and in that herein set forth there is a diametrical division of the space between the shell and the eccentrically-mounted wheel therein, and the inlet and outlet 40 let passages communicate with the several divisions of said space. In said constructions described in the prior applications this line of division is substantially permanent—as, for example, either vertical or horizontal. In the 45 present construction, wherein the shaft rotates, the line or plane of division referred to revolves on the axis of the rotating shaft, and in order that the inlet and outlet may be in constant communication with these several 50 divisions, one with one and the other with the

other, the inlet and outlet ports are also made to revolve.

Describing the invention by reference to the accompanying drawings, I point out that the apparatus is shown with its axis horizontal, but state that it may be arranged with a vertical axis, if desired. 55

Figure 1 is a vertical longitudinal section in the line 1 1 of Fig. 3, the eccentric-shaft and the anti-friction bearing-rollers being 60 shown in side view. Fig. 2 is a horizontal section in the line 2 2 of Fig. 3, the anti-friction rollers of the shaft and the sprocket-wheel applied to the shaft being shown in full view, excepting that a portion of the shaft is broken 65 away at its front end to illustrate its attachments with the casting which contains the inlet and outlet ports or passages. Fig. 3 is a transverse vertical section in the line 3 3 of Fig. 2. Fig. 4 is a transverse vertical section 70 in the line 4 4 of Fig. 2, and Fig. 5 is a perspective of one of the gates employed in the shell for engagement and co-operation with the chambered wheel.

A represents a frame having the uprights A' 75 and A² at its opposite ends.

B is a non-rotating shell secured to said uprights and composed, as here illustrated, of castings B' and B², constructed to form a cylindrical pump-chamber b, an induction-chamber 80 b', and passages b², separated by a radial partition b³ and giving communication between the chambers b and b'. The induction-chamber b' communicates with a source of supply of the liquid to be pumped, as indicated in Fig. 1, wherein B³ represents the opening of a suction or inlet pipe. Through the induction-chamber b' passes the rotating port-casting B⁴. 85

A³ is an outlet or delivery pipe arranged 90 in continuation of the opening a and bolted to the upright A².

C is a rotating shaft having an eccentric portion C', separated by a collar c from the concentric portions of the shaft, and D is a winged 95 wheel mounted loosely on the eccentric C' and occupying and gyrating within the chamber b. The shaft C rests in bearings b⁴ b⁵, formed in the shell, and, as here illustrated, anti-friction rollers c' surround the shaft in 100

said bearings. Between the hub of the wheel D and the eccentric C' are also shown anti-friction rollers c².

The wheel D is engaged with the shell B in such manner that its rotation is prevented and that it is caused to gyrate within the chamber b by the rotation of the shaft C C', and means are provided by which the space between the wheel D and its surrounding shell is diametrically divided into two chambers, one of which is the suction and the other the expulsion chamber of the pump. Said wheel D and the devices for thus dividing the space between it and the shell may be of various constructions. For example, the wheel and its connections with the shell may be like those set forth in some of the aforesaid prior applications for patent or like those pointed out in the application for patent filed simultaneously herewith and bearing the serial number 353,690. As a desirable construction, however, I here illustrate the wheel D as having radial wings d d, at the outer ends of which are flanges d', projecting laterally therefrom.

For the purpose of closing the space between the inner wall of the chamber b and that one of the wings which is opposite the wing that is for the time in contact with the shell, a series of gates are provided corresponding in number with the wings d d. Said gates are shown at E E, and in adaptation to the horizontal arrangement of the axis of the pump they are pivoted in the lateral and parallel walls of the shell B. One of said gates is shown detached and in perspective in Fig. 5, from which figure it will be seen that it has gudgeons e e at its opposite ends, which, as indicated by dotted lines in Fig. 1, enter sockets in the side walls of the shell.

The sectional form of each of the gates E E is indicated by full and dotted lines in Fig. 3, wherein it will be seen that at the inner margin of each gate there is a surface e', which is inclined to the general surface of the gate, so as to bear squarely and closely against the inner surface of the flange d' of one of the wheel's wings d when the latter is in its most retracted position with respect to the surrounding shell. Each of said gates E is also shown provided with an arm e², which is illustrated in the form of a web and located at one end of the gate. This arm projects into the space between two adjacent wings d of the wheel and is of suitable width to come into successive contact with both of said wings at the proper times to secure the vibration of the gate into and out of contact with the shell. The final closure of the gate against the shell is, however, effected by the bearing of the hook-formed flange d' of a wing most remote from the shell against the surface e' of the adjacent gate E, as seen at the left in Fig. 3, or, in other words, in the plane of the eccentric C' and diametrically opposite the wing d, which is borne by said eccentric into direct contact with the shell. This produces

the desired division of the general space between the shell and its contained wheel into two chambers, and the line of division sweeps about the axis of the shaft C and is always substantially in the plane passing through the axes of the concentric and eccentric portions of said shaft. One of these two chambers is the inlet and the other the outlet chamber of the pump, or, in other words, one is the suction side and the other the expulsion side of the pump. To give communication of the inlet and outlet with these two several chambers of the pump, the portion B' of the shell adjacent to the chamber b, which contains the gyrating wheel, is divided radially by partitions b², giving passages b², the partitions b² corresponding in number with the wings d of the wheel D, and the passages b² therefore corresponding in number with the spaces between said wings d. The partitions b² are arranged to coincide with those opposite wings d of the wheel D which are in the plane of the eccentric, so that the division of the space between the shell and the wheel D is extended to the chamber of the shell which contains the partitions b², and said division varies its position in the latter as in the former upon the rotation of the shaft C.

To provide inlet and outlet ports which shall follow the revolving suction and expulsion chambers of the pump in their revolution, the casting B⁴ is provided and fitted to rotate within the induction-chamber b' of the shell and between the outer edges of the non-revolving partitions b³ and the non-rotating head A². As a means for rotating the casting B⁴, it is provided with a socket b⁶, which fits over the adjacent end of the shaft C, and a pin b⁷ passes through the walls of the socket b⁶ and through a transverse slot c³ in the end of the shaft C. The casting B⁴ has a wall b⁸ extending diametrically across its inner open end and arranged at its inner edge or face in the plane of the division of the space within the chamber b of the shell. Said inner face of the partition b⁸ is seen in Figs. 3 and 4 partly in full and partly in dotted lines, where it will be noticed that it is of such width as to pass into apposition with one of the partitions b³ before it leaves contact with another. By this means the division of the chamber b is continued through the passages b² and through the rotating casting B⁴. At the side of the partition or wall b⁸ of said casting B⁴ corresponding with the suction-compartment of the pump-chamber b an opening is provided in said casting B⁴, giving communication between the interior of the induction-chamber b' and the spaces b² between the partitions b³, as indicated in the lower part of said casting in Fig. 1. The suction-pipe B³ therefore communicates with and supplies the appropriate or suction chamber of the pump. On the opposite side of the wall b⁸ the passage of the casting B⁴ communicates with the opening a and the delivery-pipe A³, as seen in the upper portion of said casting in said Fig. 1.

The casting B^4 is shown in double conical form with its larger end toward the pump-chamber and as having bearing at its extreme inner end against an annular seat b^0 , formed therefor upon the non-rotating portion of the shell B' , and at its opposite end against the adjacent upright A^2 about the opening a , as clearly seen in Figs. 1 and 2.

F is a ring fitted to the outer conical surface of the casting B^4 and screwed into the shell, as shown in said Figs. 1 and 2, for the purpose of centering and holding the casting B^4 in place at its inner end. F' is a similar ring fitted to the outer conical end of said casting and screwed to the upright A^2 for the proper bearing-support of the outer end of said casting. The joints between the rings F and F' and the surfaces of the casting B^4 , upon which they bear, should be substantially water-tight, and as these rings bear upon conical surfaces of said casting they may be adjusted to any degree of closeness of bearing thereon by their screw-threaded connection with the shell and head or upright.

In Fig. 2, f represents a set-screw threaded through the shell into contact with a flange f' on the ring F to retain the latter in the position given it, and f^2 is a similar set-screw threaded through the flange on the ring F' into bearing against the head A^2 to similarly retain the latter ring from movement after it has been properly adjusted.

In the construction herein described, wherein the shell does not rotate and in which the eccentrically-mounted wheel D merely gyrates within the shell B , provision is found to be necessary for the discharge of air from the chamber b , especially in starting the pump, but desirably to prevent the accumulation of air within said chamber of the shell at any time. For this purpose an automatic air-valve is herein shown at G in Figs. 1 and 3. Said valve, as here illustrated, consists of a bell g , communicating with the top of the chamber b by a passage g' and containing a loose rubber or other ball g^2 . The bell g is provided with a nozzle g^3 , which is closed or opened at pleasure by a plug-cock g^4 . When the cock g^4 is opened, air within the expulsion side of the chamber b , finding its way to the top of said chamber past the opening and closing gates E , will lift the ball g^2 and have its escape through the nozzle g^3 . After the air has been exhausted upon starting the pump the cock g^4 will be closed and will be opened again only when the pump is to be again started or when the stream thrown by the pump indicates the accumulation of air within the latter.

One object of providing the gates E with the arms e^2 , as shown, and by which they are opened by the flanges d' of the gyrating wheel, is to give free passage for air from the lower part to the upper part of the chamber b . If it were not for the desire to provide for such rise of the air within the pump, said gates E might remain in constant bearing

against the periphery of the chamber b . The gates serve to retain the wheel D , which is loose upon the eccentric, in its proper position with respect to the shell and to themselves, being the means by which the rotation of the said wheel is prevented and its gyration secured. The bearing of the wheel-wings against the gates for this purpose is in a plane transverse to the divisional plane of the pump, as indicated by the several contacts shown in Fig. 3.

In another application for patent filed simultaneously herewith, Serial No. 353,690, I have set forth another form of gate co-operating with a gyrating wheel having straight wings within a non-rotating shell. The remaining features are the same as here shown, and the claims for such other features hereto appended are not to be regarded as restricted to the particular form of the wheel and adjunctive devices as illustrated herein.

It is frequently desirable to reverse the direction of flow of water or other liquid through a pump, or, in other words, to transpose the points of induction and discharge. In the construction here shown this will be effected by merely turning the casting B^4 upside down. The pipe A^3 will then be the suction and the passage B^3 the discharge.

I claim as my invention—

1. In an apparatus of the general character described, the combination, with a non-rotating shell having a series of passages b^2 , giving communication between chambers b and b' , of a rotating shaft axial to the shell and having an eccentric portion within the chamber b , a non-rotating winged wheel occupying the chamber b of the shell and mounted loosely on the eccentric portion of said shaft, rotation of said wheel being prevented by engagement thereof with the shell, and a rotating member having a port or passage in communication with a part only of the passages b^2 and leading through the chamber b' .

2. In a rotary pump, a non-rotating shell having a chamber b and a chamber b' communicating with each other through a series of passages separated by radial partitions, a rotating shaft C , having an eccentric portion C' , a winged non-rotating wheel mounted loosely on said eccentric portion of the shaft and within the chamber b of the shell, means for connecting the wings of the said wheel with the shell, whereby the space between the shell and the wheel is diametrically divided into suction and expulsion chambers, and a rotating member B^4 , constructed and arranged to afford an outlet-passage from the expulsion side of the pump-chamber and an inlet-passage from the chamber b' to the suction side of the pump-chamber, substantially as described.

3. In combination with a non-rotating shell, a horizontal rotating shaft having an eccentric portion, a winged wheel D , mounted on said eccentric portion of the shaft, a series of gates pivoted to the shell and engaged by the

wings of the wheel, and an air-valve located in the upper part of the shell.

4. The shell B, containing the chamber b and provided with a series of radial partitions b³ and with a central shaft-bearing b⁵, supported by the partition b³, combined with the rotating shaft C, resting in said bearing b⁵ and having an eccentric portion C', and a winged wheel mounted on said eccentric portion of the shaft and engaged with the shell.

5. In the pump substantially as described, the combination, with the non-rotating shell, the rotating shaft having an eccentric portion, and the gyrating wheel mounted on said

eccentric portion of the shaft, of the conical rotating part B¹, constructed to afford outlet and inlet passages, and the adjustable rings F and F', fitted to conical surfaces of said rotating part B¹ and supported by stationary parts of the shell and frame, substantially as described.

In testimony that I claim the foregoing as my invention I affix my signature in presence of two witnesses.

ELLIICK H. GOLLINGS.
